AMPLIFIER SYSTEM

Application filed August 17, 1928. Serial No. 300,242.

The present invention relates generally to amplifier systems and particularly to such systems employing three-electrode vacuum tubes. It is a continuation in part of my 5 co-pending application Serial Number 207,- 607, filed July 22, 1927.

An object of the invention is to fix the action of amplifier systems from frequency to frequency over wide ranges of frequency in 10 those systems employing variable selective circuits to cover wide ranges of frequency, and particularly where such circuits are used with three-electrode vacuum tubes having inherent internal capacity introducing coupling effects between tube output and input 15 circuits which are not constant with frequency.

One object is to maintain overall amplification constant from frequency to frequency 20 over a wide range of frequencies, or to control the amplification in a desired way with frequency variation produced by means of selective circuits.

Another object is to controllably off-set 25 from frequency to frequency over a wide range of frequencies the reactive effects through the internal capacity of three-electrode vacuum tubes.

A further object is to maintain manually 30 operated elements of tuning devices of the system at low or ground potential to avoid well known body capacity effects particularly apparent in connection with high frequency systems, and especially so when regeneration 35 in three-electrode vacuum tube operation is present.

Other objects and the advantages thereof 40 will be readily recognized by those skilled in the art from the description to follow with the aid of the figures of the accompanying drawings.

Fig. 1 diagrammatically illustrates a system of circuits associated with a three-electrode vacuum tube to embody the features of 45 the present invention.

Fig. 2 diagrammatically illustrates employment of features of the invention in the 50 radio frequency portion of a radio receiver. Like reference characters represent like parts 55 so far as possible in the two figures.

Referring first to Fig. 1, a three-electrode vacuum tube VT is shown to have a tunable circuit including inductance coil L₂ and tuning condenser C₂ connected across its grid and filament electrodes, and there may or 55 may not be included a grid condenser C₄ and leak resistance R depending upon the function for which the tube is employed, the use or non-use of these elements under different 60 conditions of operation being well understood in the art. The plate and filament electrodes are shown connected through an indicated impedance I, which may be any of the 65 impedances encountered in connecting up vacuum tubes for operation for any one of the numerous purposes and modes of 70 employment of them now common to practice. For example, the impedance I may be the capacitive to high frequency current impedance of an audio frequency transformer in 75 the case of the tube being used as a detector of modulated high frequency currents, as is the case of tube VT in Fig. 2; or the capacitive to high frequency current impedance had when a choke coil or resistance is used as the 80 interstage coupling in a broad band high frequency amplifier; or again the variable impedance had when a tunable circuit or coupled tunable circuit is used as the interstage coupling, as is the case between tubes VT' and 85 VT in Fig. 2.

The energizing of the electrodes of the tubes is conventionally illustrated in both figures, and is too well understood to require 85 detailed reference.

The inherent internal capacity of the tube between filament and plate electrodes is indicated by the condenser C₅ connected in dotted lines. It is well known that when an 90 electrical disturbance occurs in the grid circuit of a three-electrode tube, and is repeated in the plate circuit by the repeating action of the tube, there is a reflection of the repetition back into the grid circuit by way of the 95 coupling provided by inherent capacity C₅; that the phase of the reflection depends upon the nature of the impedance, being 90° out of phase when the plate impedance is non-reactive and thus neutral or non-effective on the grid circuit energy; in assisting phase 100

when the plate impedance is inductive, thus producing increased or regenerative amplification even to self-oscillation; and opposing phase when the plate impedance is capacitive, thus decreasing amplification.

If the system is planned to cover a wide range of frequencies, as by making tuning condenser C_2 , widely variable, it is apparent that the effect of internal capacity C_s varies from frequency to frequency throughout the range. That is, the capacity remains substantially constant irrespective of frequency, and is a more effective coupling at high frequency than at low frequency. Again the impedance of any particular device used in or in association with the plate circuit can be expected to differ considerably from frequency to frequency over a wide range of frequency, so that the reaction thereof which forces energy through the internal capacity C_s is not constant with frequency. For example, if the impedance I in Fig. 1 is the capacitively reacting impedance of an audio frequency transformer such as T in Fig. 2, its capacitive reaction to high frequency currents will be less at higher frequency than at lower frequency, thus bringing about a difference in feed-back through internal capacity C_s from frequency to frequency. If the impedance I is a variable one, as is the case of a tunable interstage coupling such as that shown between tubes VT' and VT in Fig. 1, there are numerous reasons why the impedances of such a variable arrangement may not be constant with frequency. For example, if the tunable circuit is coupled to the plate circuit, as is the case of the arrangement in Fig. 2, the degree of coupling may change substantially from frequency to frequency. Also the necessity for varying the tuning condenser C_2 of Fig. 2 to have this circuit follow the tuning of the input circuit of tube VT' will change widely the ratio of inductance to capacity, which change in ratio will substantially affect the impedance.

It is thus apparent that this coupling between grid and plate circuits introduced by the filament-to-plate capacity of three electrode vacuum tubes, which permits of influencing the amplifying ability of the system enormously in the high frequency regions, together with the lack of constancy with frequency of the reactions of physically constructed electrical elements which must be used to make up circuits, makes the matter of securing uniform performance, or predetermined performance, with frequency a difficult one. Often such control over the performance with frequency is highly desirable, as for example in the case of a broadcast radio receiver which preferably should give the same performance from the neighborhood of 500 kilocycles to 1500 kilocycles, a very wide range of frequency.

Again, it is often desirable to change the

phase character of the reflection from the plate circuit back on to the grid circuit through the internal capacity of the tube from that obtained by reason of the employment of elements to perform certain required functions. For example, if the impedance I is that of an audio frequency transformer in the plate circuit of a vacuum tube used as a detector, which transformer is needed to filter the signal representing modulations from the rectified high frequency current, the inherent capacitive reactance to the high frequency currents produces a feed back through internal capacity C_s out of phase with the high frequency energy in the tuned grid circuit, which out-of-phase feed back reduces substantially the amplifying ability of the system, and also has the effect of apparently increasing the damping of the tuning in the grid circuit to lessen selectivity. In the case of the tunable inter-stage coupling the attempt to maintain the tunable coupling circuit in resonance with the tunable input circuit inevitably results in producing an inductive reaction in the plate circuit which feeds back to the grid circuit in phase with the high frequency energy therein, thereby materially increasing the amplifying ability of the tube, and so much so that if the coupling is tight oscillation will be produced on tuning the coupling circuit with respect to the tuned input circuit, an undesired effect in the case of an intended amplifying system. Further, if the effective impedance of the tunable coupling circuit back onto the plate circuit varies from frequency to frequency, as is generally the case, it may be that the reactive potential is sufficient to produce oscillation at one end of the frequency band and is not sufficient to produce oscillation at the other end of the band, thus reducing the width of the band for which the arrangement is satisfactorily operative.

These difficulties can be and have been overcome by including in systems of the kind under discussion manually variable electrical elements, which can be adjusted from frequency to frequency to overcome the difficulties as they arise. Such arrangements are more successful in the hands of skilled operators, and are undesirable and not wanted in the more popular uses of radio and like devices now being distributed for entertainment purposes.

The present invention is directed to the end of providing an arrangement in which electrical elements can be predetermined in design to overcome these difficulties in permanently fixed form, and thus avoid follow-up adjustments from point to point in a system covering a wide range of frequencies. To accomplish the result I employ an auxiliary coupling between the grid and plate circuits to oppose the effects produced by the coupling between these circuits arising from the in-

herent internal capacity of the three-electrode tube, and arrange the auxiliary coupling so that it can be predetermined to feed-back in any desired way with frequency to follow the feed-back through the tube inherent to the use of certain elements for desired functions of the system. In Fig. 1 the auxiliary coupling is shown to include a connection from the plate electrode through a condenser C_3 to a combined electromagnetic and electrostatic coupling with the tunable portion of the grid circuit, the electromagnetic coupling being that due to the coupling between coil L_1 in the auxiliary circuit and coil L_2 in the tunable circuit, and the electrostatic coupling being that due to condenser C_1 common to the two circuits. With the connections shown, the polarity of the electromagnetic coupling is correct to phase with the electrostatic coupling. In my co-pending application 48,936 of August 8, 1925, I have set forth in detail how the energy transfer of an electromagnetic coupling decreases with decrease of frequency and how the energy transfer of an electrostatic coupling of the kind shown increases with decrease of frequency, and how the two transfers can be combined to produce an over-all transfer remaining substantially constant with frequency, or varying in any predetermined way with frequency, by proper selection of the relative degrees of the two coupling effects, and have particularly pointed out how I principally control the resultant effect by choice of the capacity relations between tuning condenser C_2 and coupling condenser C_1 .

It is therefore obvious that with this combination of coupling I can predetermine an auxiliary feed back from the plate circuit to the grid circuit that will oppose in any desired way the feed back due to internal capacity C_5 acting in accordance with the impedance I of the particular element used in the plate circuit of the system, and can thus make the action of a system such as that shown in Fig. 1 substantially constant with frequency over a very wide range of frequencies, or vary in any predetermined way with frequency from the inherent way of action imposed by internal capacity C_5 and the nature of impedance I .

The connection as shown opposes the feed back through the tube no matter what may be the nature of the reactance of the impedance element I , this because the combined electromagnetic and electrostatic coupling reverses the phase of the reaction passing through condenser C_3 . Thus, if the reaction in the plate circuit is capacitive to produce a deamplifying feed back through C_5 , the feed back through the auxiliary circuit and its combined coupling produces a regenerative effect to lessen de-amplification any desired amount, or reverses it to produce regenera-

tive amplification, and may be even adjusted strong enough to produce oscillation, this either by adjusting the value of condenser C_2 or the degree of electromagnetic and electrostatic couplings.

There is shown in dotted lines a source S of alternating current coupled to the input of the system through coil L_3 , which source may be one of high frequency modulated currents to be either amplifiedly repeated and passed on to a subsequent system by means of proper choice of element for impedance I , or amplifiedly detected for transfer to a responsive device or audio amplifier. Or the source S may be one of continuous or unmodulated currents, in which case the auxiliary circuit may be adjusted to give enough feed back to produce oscillation for so-called self-heterodyne reception of the continuous waves, and in this case it is possible to so adjust the auxiliary circuit and its coupling that the system may be maintained slightly in oscillation throughout the entire range of tuning covered by condenser C_2 , which effect has heretofore not been possible with the feed-back coupling arrangements between grid and plate circuits of systems used in connection with so-called self-heterodyne reception. Or the system may be used simply as an oscillation generator for producing high frequency oscillations for any purpose, but with which it is desired to be certain of producing substantially the same magnitude of oscillation throughout a wide range of frequencies merely by varying the tuning condenser C_2 . In this case the source S would be eliminated, and an element for impedance I chosen to pass the high frequency oscillations out of the system to any desired point of use.

It will be further noted that in the arrangement shown the coupling condenser C_1 and the tuning condenser C_2 are so related that the tuning condenser C_2 is directly connected to the filament system of the tube, the point of lowest high frequency potential of the system, and may be thus connected to a ground G as is common in vacuum tube amplifier systems. Assuming that the condenser C_2 is of the usual stator-rotor type, the rotor side can be the grounded side, thus eliminating body effects by reason of the operator having to handle the rotating arrangement. This form of connection varies the difference of potential across condenser C_2 with frequency, and therefore the difference of potential across the grid and filament of the tube, as the ratio of the capacity of condenser C_2 to the capacity of condenser C_1 is varied by altering the capacity of condenser C_2 for tuning. In general practice the capacity of coupling condenser C_1 is large compared to the capacity of tuning condenser C_2 , so that the ratio will not be changed to such a degree that the flexibility of the combined electromagnetic and electrostatic coupling

will not permit of an adjustment to overcome the lack of constancy introduced by such an arrangement. This mode of employing the combined electromagnetic and electrostatic coupling is of particular value in connection with the so-called single dial control of a multiplicity of stages of radio frequency amplification, where it is desirable that all of the rotors of the several stages connected through a single control element be at one and the same potential and the lowest potential.

In Fig. 2 the features of the invention are shown adapted to a radio receiver as follows:

18 Tube VT is connected and energized for detection of high frequency modulated currents amplified in tube VT' and transferred to tube VT by way of a tunable coupling circuit including inductance L_2 and tuning condenser C_2 . In this case the impedance of audio frequency transformer T in the output circuit of the detector reacts capacitively to the entire high frequency band which tunable circuit L_2 , C_2 covers, thus causing the system to de-amplify for all frequencies while detecting. The capacitive reactance of transformer T is indicated by the condenser C_6 in dotted lines. The de-amplifying feed-back through the tube is opposed by an auxiliary circuit coupling the plate circuit and the grid circuit by way of condenser C_3 and the combination of electromagnetic coupling between coil L_1 and L_2 and electrostatic coupling afforded by condenser C_1 as described in connection with Fig. 1. The feed-back by means of the auxiliary coupling can be made of any degree desirable, so that the detector tube may be made neutral in the matter of over-all feed-back, or may be made to regeneratively amplify to any desired degree by adjustments described in connection with Fig. 1, and the effect made constant with frequency or varying with frequency in a predetermined way as before described.

45 Tube VT' is connected and energized to amplify at high frequency, the high frequency modulated currents being impressed upon the tunable input circuit L'_2 , C'_2 , through an antenna W connected to ground G by way of inductance L'_1 and condenser C'_1 , thus giving a combined electromagnetic and electrostatic coupling between the antenna and the tunable input circuit. A low capacity high frequency choke coil K, shunted around coupling condenser C'_1 , provides for a direct current bias to the grid of tube VT'. The output circuit of tube VT' is coupled electromagnetically and electrostatically to the detector tunable circuit L_2 , C_2 through the inductive coupling between coil L_1 and coil L_2 , and coupling condenser C_1 . This tunable inter-stage coupling may be responsible for a variable with frequency impedance in the plate circuit of tube VT', and if the coupling is tight enough there will inevitably result

sufficient inductive reaction as tunable circuit L_2 , C_2 is adjusted to produce oscillation by reason of feed back through inherent tube capacity C' , unless the effect is opposed to sufficient degree. The necessary opposition is provided for by means of auxiliary feed back circuit C'_3 , L'_1 , and C'_1 , which can be adjusted as before described to give any amount of auxiliary feed back needed and to act in any desired way with frequency.

It will be noted that in case of Fig. 2 the combined coupling in the case of both tubes is made to serve the double function of transferring energy forward and transferring energy backward from plate to grid circuit. It is not difficult to bring this double function into satisfactory operation, because the combined coupling may be primarily designed to give the right amount of energy transfer forward, and the feed back effect then satisfactorily controlled through selection of the values of feed back condensers C'_3 and C_3 . However, the energy transfer coupling can be made independent of the feed back coupling as indicated in Fig. 1. The flexibility of the combined electromagnetic and electrostatic coupling permits of adjustment to arrive at an opposing energy that will take care of the resultant tube feed-back energy of a combination of effects inherently different from frequency to frequency, whereby a substantially over-all uniform amplification effect for the system, or variation from this uniform effect if wanted, is possible.

50 It will be noted that tuning condensers C'_2 and C_2 each have one element at a common or ground potential, so that the arrangement provides for connecting the rotors of these conductors to the same shaft for single dial control without introducing difference of potential difficulties.

55 The high frequency, low capacity choke coil K permits of energizing the plate electrode of plate VT' around coupling condenser C_1 without materially affecting the coupling conditions. The electrodes of the tube are indicated in a conventional manner as suitably energized for the intended purposes of operation.

60 The invention is one capable of numerous applications in the various practices of the art which will be readily apparent to those skilled in the art, and no limitations are intended by reason of the selection of the particular systems embodied in the drawings for descriptive purposes.

65 Having thus described my invention, I claim:

1. The combination of a three-electrode vacuum tube, an input circuit, an output circuit, a tunable circuit in one of said circuits, an impedance element in the other of said circuits, and a connection from a potential point created by said impedance element, said con-

- nection including a condenser and an in-phase combination of electromagnetic and electrostatic coupling to said tunable circuit.
2. The combination of an amplifier having 5 input and output circuits, a tunable circuit forming a part of one of said circuits, an electromagnetic coupling linking said tunable circuit with the other one of said circuits, and a second coupling therebetween adapted to 10 transfer energy in phase with said electromagnetic coupling, said second coupling having an energy transfer-frequency characteristic the reverse of that of said electromagnetic coupling.
3. The combination of an amplifier having 15 input and output circuits, a tunable circuit forming a part of one of said circuits, a pair of in-phase couplings linking said tunable circuit with the other one of said circuits, said 20 couplings having reversed energy transfer-frequency characteristics.
4. The combination of a three-electrode 25 vacuum tube having inherent capacity between its electrodes, a tunable input circuit, an output circuit including an impedance element producing a non-constant impedance with frequency variation, and means for opposing in kind the resulting non-constant 30 with frequency feed-back through said tube capacity comprising a circuit connected between a potential point of said impedance and the cathode of said tube, said circuit including a series connected condenser outside of said tunable circuit, a second series connected condenser included within said tunable circuit, and an inductance coil coupled to an inductive coil in said tunable circuit with a polarity to transfer energy in phase 35 with that transferred electrostatically by said 40 second condenser.
5. The combination of a three-electrode 45 vacuum tube having inherent capacity between its electrodes, an input circuit including a circuit tunable over a wide range of frequencies, means for supplying currents of different frequencies to said tunable circuit for selection thereby, an output circuit including an associated system producing a non-constant 50 impedance with frequency as said tunable circuit is varied, whereby the amplification of said tube is non-constant with frequency by reason of varying feed-back through said inherent tube capacity, and means associated with said input circuit for 55 automatically variably modifying with frequency the effect of the non-constant character of said feed-back whereby the overall amplification of said system is maintained substantially constant with frequency.
6. The combination of a three-electrode 60 vacuum tube, a tunable circuit including a variable condenser connected across the grid and cathode of said tube including a direct connection to said cathode, an output circuit, and a combined electromagnetic and electro- 65
- static coupling between said output circuit and said tunable circuit, said electrostatic coupling including a condenser in said tunable circuit in series with said variable condenser and common to at least a portion of said output circuit, one terminal of said coupling condenser being connected directly to the cathode of said tube. 70
7. The combination of a three-electrode 75 vacuum tube, a tunable circuit including a variable condenser connected across the grid and cathode of said tube including a direct connection to said cathode, a circuit electromagnetically and electrostatically coupled to said tunable circuit, said electrostatic coupling comprising a condenser in said tunable circuit in series with said variable condenser and common to both circuits, one terminal of said coupling condenser being connected directly to the cathode of said tube. 80
8. The combination of a plurality of three-electrode vacuum tubes connected in cascade relation, a circuit at substantially ground potential linking the cathodes of said tubes, tunable circuits each including a mechanically operated tuning condenser connected to the grids of said tubes and directly to said grounded cathode circuit, and circuits coupled to each of said tunable circuits through a combination of electromagnetic and electrostatic couplings, said electrostatic couplings each comprising a condenser in each of said tunable circuits in series with said tuning condensers and common to both circuits, one terminal of each of said coupling condensers being connected directly to said grounded cathode circuit, whereby the movable elements of all of said tuning condensers are maintained at ground potential. 90
9. In combination, a source of signal energy, an oscillation generator comprising an electron discharge tube having a tunable input circuit coupled to said source and an output circuit, an impedance element in said output circuit, and a pair of in-phase couplings between the output and input circuits, said couplings having reversed energy transfer-frequency characteristics. 100
10. An oscillation generator adapted to produce high frequency oscillations of substantially constant magnitude over a desired frequency range comprising a space discharge tube having a tunable input circuit and an output circuit, an impedance in the output circuit, a path from a potential point created by the impedance, and said path including an in-phase combination of electromagnetic and electrostatic coupling to the input circuit. 110
11. A regenerative amplifier circuit including a multi-electrode tube provided with a tunable input circuit and an output circuit, a load in the output circuit, and a feed back path between the output circuit and the input circuit, said path including a pair of mutual impedances of the same sign, but 120
- 125

opposite frequency characteristics, designed to maintain a predetermined amplification value throughout a range of frequencies.

12. A stabilized amplifier circuit including a multi-electrode tube provided with a tunable input circuit, and an output circuit, a load in the output circuit, and a feed back path between the output circuit and the input circuit, to counteract the inherent feed back through the tube electrodes, said path including a pair of mutual impedances of the same sign, but opposite frequency characteristics, designed to maintain a predetermined amplification value throughout a range of frequencies.

10 In witness whereof, I hereunto subscribe my name this 16th day of August, 1928.
